(57) CLAIM

The ornamental design for a gift bag with water container, as shown and described.

DESCRIPTION

FIG. 1 is a front perspective view showing the gift bag with water container in an open configuration embodying my new design;

FIG. 2 is a rear perspective view showing the gift bag with water container in a folded configuration embodying my new design;

FIG. 3 is a front view of the open configuration thereof showing the water container;

FIG. 4 is a rear view of the open configuration thereof;

FIG. 5 is a right side view of the open configuration thereof;

FIG. 6 is a left side view of the open configuration thereof;

FIG. 7 is a top plan view of the open configuration thereof; and,

FIG. 8 is a bottom plan view of the open configuration thereof.

The broken lines in FIGS. 1 and 3 is for illustrative purposes only and forms no part of the claimed design.
